UNITED STATES PATENT OFFICE

LEO E. EVSLIN, OF ATLANTIC CITY, NEW JERSEY

ADJUSTABLE TOOTHBRUSH

Application filed July 23, 1926. Serial No. 124,364.

This invention relates to tooth brushes and refers more particularly to a device that is convenient to handle and also capable of being sterilized.

5 One object of the invention is in the provision of a tooth brush which can be held at various angles, whereby all exposed parts of a tooth is readily reached thereby insuring thorough cleansing.

10 A further feature is in the provision of a device, the elements of which are removable and replaceable whereby it is made possible to discard old and unclean brushes and substituting new or freshly sterilized.

15 A still further object is in the provision of a massaging element for the gums, tending to stimulate circulation therein, thereby lessening chances of infected gums, pyorrhea and other diseases of those members.

20 These and other useful results are obtained by the novel construction and arrangement of parts hereinafter described and illustrated in the accompanying drawings, in which:—

25 Figure 1 is a fragmentary partial sectional, partial side elevational view of a simple form of the improved brush.

Figure 2 is a partial sectional view of a brush head.

30 Figure 3 is a side elevational view of another type of a brush head.

The device shown in Figure 1 consists of a plain handle 32 in which is set a stem 33 bent into a shape whereby a brush may be used 35 in the mouth to the best advantage.

An outer shallow conical shell 34 may be secured by a collar 35 to the stem 33, which has a reduced element 36 extending axially into the shell and through an inner shell 37, 40 between which is disposed a circular row of bristles 38.

The extremity of the rod is upset to clamp the shells in tight relation and held by Y branches 39, while the interior of the inner shell is filled with rubber or like vulcanizable substance acting as a filler to prevent an undesirable accumulation of tooth paste or the like used in connection with the brush, and it will be noted that a specially effective form 45 of tooth brush is thus provided.

Figure 2 discloses a similar shaped brush consisting of a circular or rather conical row of bristles 42 held between inner and outer conical shells 43 and 44 respectively, the latter having an extending knob 45 at its base 55 suited to engage in a socket.

The brush shown in Figure 3 consists of bristles 46, the outer and inner periphery of which form a circle, set in semi-circular shaped cup or body 47. Rigidly engaged with the body is a straight shank having a globular element 48 to be tightly held in the handle or casing and used for cleaning the outer surfaces of the teeth.

While preferred embodiments of this device have been shown and described, it will be understood that changes in the form, arrangements, proportions, sizes and details thereof may be made without departing from the scope of the invention as defined in the 70 appended claim.

Having thus described my invention, what I claim as new and desire to secure by Letters Patent, is:—

75 A manually operable tooth brush comprising a solid handle, an angularly bent stem fixed therein, a forked element projecting from the end of said stem, a cup through which said forked element extends, said cup containing a filler intermingling with the 80 prongs of the fork, a conical shell spaced circumjacent said cup, said shell having a collar fixed on said stem adjacent the fork, and a thin annular brush secured between said shell and said cup.

85 In testimony whereof I have affixed my signature.

LEO E. EVSLIN.
